OBJECTIVES FOR TAKING, PRINTING, AND
PROJECTING LENTICULAR FILMS

Kurt Räntsche, Teltow-Seehof, near Berlin, Germany, assignor to Opticolor, Aktiengesellschaft, Glarus, Switzerland, a corporation of Switzerland

Application June 15, 1934, Serial No. 730,715
In Germany June 22, 1933

7 Claims. (Cl. 95—2)

The invention relates to objectives for taking, printing and projecting lenticular films and more particularly to such objectives which are associated with a multicolor screen or are provided with a diaphragm which to a certain degree has the effect of a polychromatic screen.

If the image of the multicolor screen or of the diaphragm seen from the film appears distorted, color dominants will be caused. The distortion is especially great with such diaphragms or screens which are mounted in the interior of the objective, this being corrected as a whole, its single parts having no or an insufficient correction.

If the multicolor screen and the adherent diaphragm are mounted in the interior of the objective, the bands of the screen are seen in another greatness from the middle of the picture field but from a point lying at the margin of the picture field. A band at the margin of the screen e. g. being seen comparatively greater from the margin of the picture field than a middle band, this lateral band will predominate in its color towards the margin of the taken or printed or projected picture. Quite the contrary results, if a lateral band is seen from the margin of the picture field comparatively smaller than a middle band.

These dominants may be avoided by the known means providing a diaphragm remote from the screen, which is only effective for such parts of the beam of light which go towards or away from the margin of the picture field.

The fault caused by the distortion is even stronger if diaphragm and multicolor screen are separated. With such objectives the filter consists of a great number of bands, the colors of which periodically repeat. A multicolor screen with the three elementary colors red, green and blue being taken as basis, the three middle bands may be continued by two other bands also with the colors red, green or blue on every side of the screen, the colors recurring cyclicly over the whole filter. The diaphragm should be shaped in this case in such a manner, that the ratio of the areas of different color seen from different points of the picture field is constant. The diaphragm e. g. may have a rectangular shape and may be chosen so wide, that the three middle bands of the color filter are to be seen from the middle of the picture field. Four different bands are generally seen from the points lying beyond the middle of the picture field, two bands having the same color. These bands shall supplement one another in the amount of their whole

area in such a manner, that color falsifications do not arise. Other shapes of diaphragms, for instance a hexagon, may be applied instead of the rectangular diaphragm.

It is a condition which is to be observed with objectives the diaphragm of which is separated from the filter, that the bands of the same color shall have the same width, eventually inclusive of opaque intervening spaces. In this case the color filter is often mounted in front of the objective, for instance in the front focal plane, the diaphragm being mounted in the interior of the objective.

For a fuller explanation of the invention, its objects and advantages reference will be made to the accompanying drawing wherein the same reference characters denote the same parts throughout and in which:

Fig. 1 is a diagram illustrative of the principle of the optical systems comprising an objective, a diaphragm and a screen, the screen being distant from the diaphragm;

Fig. 2 shows a sectional side view of such an optical system;

Figs. 3 and 4 are illustrative of the defect, which is to be observed with the existing objectives making them inappropriate for use with lenticular films;

Figs. 5—10 are diagrams of different color screens embodying the invention.

In Fig. 1 the film is situated at 1. The image of the diaphragm seen from the film (the pupil of emergence of the objective) is indicated by 2, the image of the screen seen from the film being placed at 3. The image of the screen is situated in the finite. However, the following considerations are exactly the same, if the image of the screen is placed in the infinity. From the point 4 lying in the middle of the film gate the three middle bands G, R, B of the filter 3 will be seen through the pupil 2, which for instance may have a rectangular shape. From a point 5 on the margin of the film gate instead of the band B the band B₁ of the same color is visible and of the band R only a part, but therefore the band R₁ will be seen. If for instance a hexagonal diaphragm is used instead of the rectangular diaphragm, the bands G and B are to be seen from the point 4 cut in the height in diagonal direction and therefore edges of the bands B₁ and G₁ are visible.

In Fig. 2 an objective is represented, the pupil and the image of the screen having the same position as in Fig. 1. The objective 6 in the interior contains the diaphragm 7, which is to be seen

from the film at the place 2. Before the objective there is situated a color screen 8, which seen from the film seems to be placed at 3.

Hitherto the wide of the filter bands and the aperture and shape of the pupil 2 were only chosen according the method illustrated in Fig. 1.

This method however is not sufficient, and defective objectives are produced. The diaphragm 7 being placed in the interior of the objective and for instance having a rectangular shape, it is not seen from the film 2 as rectangular but as a quadrangle with crooked lines. In Fig. 3 the bands R₁, B₁, G₁, R₂, B₂, G₂, R₃ are shown in a front view. The color screen being seen in this example through the whole objective, these bands appear wholly or at least approximately undistorted. From the point 4 of the film gate that part of the color screen is visible, which consists of the quadrangle 9 with crooked lines. It is evident, that the whole visible area of the bands G and B is little greater than the visible area of the band R. Beyond this little parts of the bands B₁ and G₁ are to be seen. Looking through the objective from a point out of the optical axis for instance point 5, that part of the color is visible, which is represented by the quadrangle 10. This quadrangle is distorted in quite another way than the quadrangle 9. Thus, the band G₁ is seen greater than for instance the band B, and the whole area visible of the bands R and R₂ is still greater.

For these parts of the film gate the color determined by R will considerably predominate. In the same manner the same color predominates for a point situated on the opposite side of the film gate. However, for an interjacent point of the picture field, from which the bands R₁ or R₂ on the margin of the color screen are not yet to be seen, the colors predominate, which are determined by the bands B₁ or G₁. It is evident, that a change of the different predominating colors results in advancing in lateral direction over the picture field.

The manner in which this change proceeds is to be understood from Fig. 4. In this figure the abscissas represent the distances of the points of the film gate from the perpendicular through the middle of the gate (parallel to the direction of the color bands). The three curves r, g, and b illustrate which parts of the areas of the color screen are to be seen from the points of the film gate. The portions of red, green and blue light effective for the middle of the film gate are subtracted, the curves only representing the difference from the proportion of the bands of different colors in the middle of the film gate. The meaning of the curves is as follows: Advancing from the middle of the film gate towards the margin, for instance to the point 11, the equal area of the bands of the colors determined by G and R is seen as from the middle of the film gate.

However a much greater part of the area of the color indicated by B is to be seen, and the difference from the middle of the film gate amounts to nearly 5% at point 11. In a greater distance from the middle of the gate the surplus portion of the color determined by B continually increases and reaches nearly 10%, finally diminishing again. There a predominating of the color determined by R is to be observed, as it is shown by Fig. 3. The bands of the color determined by R will be seen on the margin with a much greater area than from the middle.

There are the same proportions in advancing from the middle of the film gate towards the

other side. At first the color determined by G is predominating, and on the margin the color of the band R₁ predominates again.

The defects arising with the screens known hitherto were explained above by the example of an objective, comprising a color screen, which consists of seven different bands. The defects are the same, if the screen consists of more or less differently colored bands. If the distortion of the pupil seen from the film is not cushion-like as illustrated in Fig. 3, but if it is barrel-shaped, the preceding facts are also unchanged in principle.

For removing the defects described above diaphragms or diaphragming means are used. 15 These are preferably arranged immediately on the color screen. Fig. 5 represents a front view of the means which, though not wholly removing the defects, considerably reduce them. The opaque strips of the color screen represented in 20 Fig. 5 being arranged between the single bands of the color screen, have a different width. They are comparatively narrow between the bands G, R, and B and only of such a width, that the undesirable diffusion between the parts of the 25 photographic layer appertaining to the different bands of the screen is reduced to a tolerable degree. However, the strips between the bands on the margin of the screen have a much greater width, the curves r, g, and b represented in Fig. 4 30 thereby being leveled down. The course of these curves is influenced in such a manner, that they are partly positive and partly negative and run closely to the abscissa axis.

Another means which removes the dominants 35 with greater success is represented in Fig. 6. This figure shows a sectional view of a color screen consisting of seven bands. Grey-wedges K₁ to K₄ are laid on the bands R₁, B₁, G₁, and R₂.

The course of the characteristic curves of those 40 wedges is easily chosen in such a manner using the curves represented in Fig. 4 that no color falsifications arise, the curves r, g, b of Fig. 4 becoming completely rectilinear. To avoid an undesirable prism effect the part left free between 45 the wedges R₁ to R₁₁ should be covered by a layer S of clearly transparent material. Moreover, with these and also with the other color screens which should be made according to the invention all means known in manufacturing 50 screens may be applied. For instance, opaque strips may be included between the color bands and cover-glasses &c. may be used.

Another modified color screen is shown in Fig. 7 in a sectional view. For the sake of an easier 55 manufacture the grey-wedges K₂ and K₃ of Fig. 6 are replaced by two grey-screens L₂ and L₃ in form of steps.

Moreover grey-screens L₁ and L₄ are arranged on the bands R₁ and R₂. The whole is covered 60 with a layer S of transparent material to obtain an exact parallelism of the faces of the screen.

The same effect which is obtained with the screens represented in Figs. 6 and 7 should be reached to a certain degree by giving a greater 65 transparency to the bands on which the grey-wedges are arranged.

Instead of the grey screens diaphragms according to Figs. 8 and 9 may be used. These figures show front views of color filters embodying 70 the invention. The bands R₁, B₁, G₁, and R₂ of Fig. 8 are covered with tapering diaphragms M₁ to M₄. These should be made of an opaque material, for instance cut out of black paper and the like and pasted on the bands. They are ar- 75

ranged on the bands in middle height for being also visible and effective for the points on the upper and the lower margin of the film gate. Sometimes it should be advantageous to provide 5 on the screen not only one but several of the tapered masks. Such a filter consisting of six bands is shown in Fig. 9. Tapered diaphragms M_1 to M_4 and M_1' to M_4' are arranged two by two on the bands R_1 , B_1 , G_1 and R_2 . To show 10 in which circuit the masks have to be arranged on the bands, the part of the screen is represented which is visible from a point in the corner of the film gate. The diaphragms should be arranged in such a manner that they are visible 15 from all points.

Instead of the masks represented in Fig. 9 a great number of very thin and tapered diaphragms should be used and should be arranged at the same distances over the length of the 20 bands to be covered. If the number of the masks is great enough, the effect is similar that of a grey-wedge laid on, and no defect arises if from each point of the film gate only a part of the masks of each band is visible.

25 With the examples described above it has been suggested, that the distortion of the diaphragm seen from the film-gate is cushion-like. If the distortion is barrel-shaped, the defects produced by it should be eliminated by arranging the diaphragms not on the bands on the edge but on the middle of the screen.

Such a color screen, the middle bands of which are diaphragmed, is shown in a front view in Fig. 10.

35 The bands G, R, and B are covered in the middle by the masks M_5 , M_6 , and M_7 . Instead of these masks the other means represented in Figs. 5 to 9 may be applied.

The scope of the invention has been illustrated 40 above for such optical systems, with which a color screen consisting of one or more bands is associated with the objective. However, the invention also comprises optical systems used in copying, a diaphragm being arranged at the place 45 of the color screen. This diaphragm may be used for copying with different intensity the colors belonging to the different bands. In this case the diameter of the aperture of the diaphragm should not be chosen only proportionally to the quantities 50 of light which are to be used in copying, but it has to be taken into account that the shape of the aperture is changed by the distortion.

I claim as my invention:

1. An optical system for use with lenticulated 55 films comprising an objective and a diaphragm, a color filter spaced from the diaphragm and comprising recurrent series of zones of different color values, the sum of the values in any one series giving substantially the effect of white light, and masking means applied to certain of 60 said zones, the amount of masking effected on the various zones progressively changing from the center of the filter towards the edge zones.

2. An optical system for use with lenticulated 65 films comprising an objective and a diaphragm, a color filter spaced from the diaphragm

and comprising recurrent series of zones of different color values, the sum of the values in any one series giving substantially the effect of white light, and masking means applied to certain of said zones, said masking means being so arranged 5 and constituted that the product obtained by multiplying the area of any zone by its transparency is constant, as viewed from different points on the film used with the objective.

3. An optical system for use with lenticulated 10 films comprising an objective and a diaphragm, a color filter spaced from the diaphragm and comprising recurrent series of zones of different color values, the sum of the values in any one series giving substantially the effect of white 15 light, and masking means applied to certain of said zones, the amount of masking effected on the various zones progressively increasing from the center of the filter towards the edge zones.

4. An optical system for use with lenticulated 20 films comprising an objective and a diaphragm, a color filter spaced from the diaphragm and comprising recurrent series of zones of different color values, the sum of the values in any one series giving substantially the effect of white 25 light, and masking means applied to certain of said zones and comprising wedge-shaped dia- phragms varying in width transversely of said zones and applied to the zones which appear to be too great because of the distortion of the 30 objective.

5. An optical system for use with lenticulated 35 films comprising an objective and a diaphragm, a color filter spaced from the diaphragm and comprising recurrent series of zones of different color values, the sum of the values in any one series giving substantially the effect of white light, and masking means applied to certain of said zones and comprising wedge-shaped dia- phragms varying in opacity transversely of said 40 zones and applied to the zones which appear to be too great because of the distortion of the objective.

6. An optical system for use with lenticulated 45 films comprising an objective and a diaphragm, a color filter spaced from the diaphragm and comprising recurrent series of zones of different color values, the sum of the values in any one series giving substantially the effect of white light, and masking means applied to certain of 50 said zones and comprising wedge-shaped dia- phragms varying in width and in opacity trans- versely of said zones and applied to the zones which appear to be too great because of the distortion of the objective.

7. An optical system for use with lenticulated 55 films comprising an objective and a diaphragm, a color filter spaced from the diaphragm and comprising recurrent series of zones of different color values, the sum of the values in any one 60 series giving substantially the effect of white light, and masking means applied to certain of said zones and comprising a plurality of dia- phragms applied to one or more of said zones and extending transversely thereof.

KURT RÄNTSCH.
